(57) **CLAIM**

The ornamental design for a car aromatherapy diffuser, as shown and described.

DESCRIPTION

FIG. 1 is a perspective view of the car aromatherapy diffuser showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view, of circled portion 9, of FIG. 1, thereof.

The evenly broken lines throughout the drawing figures depict portions of the car aromatherapy diffuser that form no part of the claimed design.

The dot-dash broken lines depict boundaries of the FIG. 1 and FIG. 9 enlargement that forms no part of the claimed design.
